CHAIR

Earl F. Hamilton, Columbus, Ind., assignor to Hamilton Cosco, Inc., Columbus, Ind., a corporation of Indiana

Filed Sept. 10, 1962, Ser. No. 71,633

Term of patent 14 years

(Cl. D15—1)

FIG. 3.

FIG. 1 is a front elevation of a chair showing my new design;

FIG. 2 is a side elevation thereof; and

FIG. 3 is a rear elevation thereof.

The dominant features of my design are shown in full lines in the drawings.

The characteristic features of the design reside in the provision of the interlocking arcuate back members in combination with the tubular frame member, all as shown.

I claim:

The ornamental design for a chair, as shown and described.
